William H. Hamilton Inventor:

By Geo. K. Woodward

Atty.

UNITED STATES PATENT OFFICE.

WILLIAM H. W. HAMILTON, OF BAKER, OREGON.

CHECK-BOOK.

1,398,508.

Specification of Letters Patent. Patented Nov. 29, 1921.

Application filed November 15, 1920. Serial No. 424,018.

To all whom it may concern:

Be it known that I, WILLIAM H. W. HAMILTON, a citizen of the United States, and a resident of Baker, in the county of 5 Baker and State of Oregon, have invented a new and useful Improvement in Check-Books, of which the following is a specification.

My invention relates to check books, and 10 more especially to pocket check books, and its object, broadly speaking, is to provide such check book with a simple, inexpensive device formed integral therewith for delimiting the amount for which each check 15 is drawn.

With this object in view my invention comprises a check book provided with means permanently secured thereto for punching the marginal or other portions of 20 each check to delimit the amount for which the check is drawn, and such means preferably consist in a snap fastener whereby the flap attached to one of the check-book cover-members may be secured to the other 25 cover-member, such snap fastener comprising a head constructed to perform the function of a punch and a socket arranged to cooperate therewith.

In this manner I obviate the necessity for 30 employing a check writing machine, or a check protecting apparatus or other means independent of the check book for preventing the raising of the amount for which the check is drawn, and provide a check- 35 protecting device which is so inexpensive that banks can supply it without charge to their depositors and which, being permanently associated with the check book, is always ready at hand for use, and cannot be 40 lost or mislaid.

The foregoing and other advantages of my invention will more fully appear from the following detailed description and the distinctive features of novelty will be there- 45 after pointed out in the appended claims.

In the drawings which accompany and form a part of this specification—

Figure 1 is a plan view of a check book embodying my invention.

Fig. 2 is a section taken on the line 2—2 of Fig. 1.

Fig. 3 is a plan view of one form of check that may be used with my improved check book.

Fig. 4 is a vertical section on an enlarged scale of a combined snap fastener and punch.

Fig. 5 is a plan view of said snap fastener. Fig. 6 is a plan view showing the manner in which a check may be delimited by means of my check book.

In the particular drawings selected for illustrating the principle of my invention, 60 10 represents the under cover-member of a check book, said cover-member terminating in a flap 11, and 12 represents the upper cover-member of said check book.

The stubs of the checks are bound together in any suitable manner, as for example, by the staple 13 and the tab 14 is arranged to slip into the pocket in the under cover-member 10 formed by the flap 15, in the usual manner. By this or any other suitable means, the stubs may be removed from the cover and a new set of checks inserted 70 therein.

The forward end of the flap 11 is cut away to form a tab 16 to which is secured the socket 17 of a snap fastener. The interior of the socket is enlarged as shown at 18, and the aperture at the outer end thereof is 80 slightly smaller in diameter than the head 19, which is secured to the cover-member 12. The head is cylindrical and its outer end is preferably normal to its longitudinal axis, as distinguished from the usual snap 85 fastener in which the head is rounded, so that it will perform the function of a punch, and it is provided near its base with a peripheral groove 20, into which the rim of the socket will snap when the head is pushed 90 home. By enlarging the inner wall of the socket, as shown at 18, and splitting said socket vertically, as shown at 21, sufficient elasticity is imparted to the socket to enable the outer end thereof to snap into said 95 groove 20. The inner end 22 of the socket is open to permit the escape of the punchings.

It will be understood that I do not limit myself to the specified form of combined snap 100 fastener and punch herein specifically shown and described, and that my invention resides broadly in a two-part check-limiting device, such for example, as a snap fastener, the head of which is constructed to operate as 105 a punch, one part of which device is attached to one cover-member and the other to the other, so that, being fixedly secured to the check book, the device will always be ready for use and cannot be lost or mislaid. 110

I prefer to use with my improved check-limiting device checks having figures printed

on the margins thereof, although it will be understood that such figures may be printed on other portions of the check. As indicated, each check carries a notice that it is 5 not good for more than the smallest amount punched therein, and is void if there is more than one punch mark in each column. In order to delimit a check by means of the present invention, the check, after being 10 filled in with the name of the payee and the amount for which it is drawn, is torn from the stub and placed across the check book with the proper figure over the punch or head of the snap fastener 19. The socket is 15 then pressed down so that the head enters thereinto and punches the check at the proper point. Each column is provided with a space marked "None" so that in case no figure of any column is necessary in order 20 to make up the amount for which is drawn, such space in said column will be punched. Having thus described an illustrative embodiment of my invention, without however, limiting myself thereto, what I claim and 25 desire to secure by Letters Patent is—
1. A check book comprising in combination a cover, a flap attached to one cover-member, and check punching means, said means consisting of a snap fastener having 30 one element secured to said flap and the co-operating element thereof secured to the other cover member.
2. A check book comprising in combination a cover, a flap attached to one cover-member, a snap fastener having one element secured to said flap and the co-operating element thereof secured to the other cover-member, the head of said snap fastener being cylindrical and the outer end thereof being normal to its longitudinal axis.
3. A check book comprising in combina-

tion a cover, a flap attached to one cover-member and check punching means, said means consisting of a snap fastener comprising a socket and a co-operating head, said 45 socket being secured to said flap and said head being secured to the other cover-member.

4. A check book comprising in combination a cover, a flap attached to one cover-member, and check punching means, said means consisting of a snap fastener comprising a socket and a co-operating head, the 50 socket of said snap fastener being secured to said flap, said socket being opened at its 55 inner end, and the head of said snap fastener being secured to the other cover-member.

5. A check book comprising in combination a cover, a flap attached to one cover-member, and check punching means, said 60 means consisting of a snap fastener comprising a socket and a co-operating head, said socket being secured to said flap and said head being secured to the other cover-member, the head of said snap fastener having 65 a peripheral groove near its base for receiving the rim of said socket.

6. A check book comprising in combination a cover having two members, and a check limiting device having two parts, the 70 parts of said device being secured respectively to the members of said cover.

7. A check book comprising in combination a cover having two members and a punching device having two parts, the parts 75 of said device being secured respectively to the members of said cover.

In testimony whereof, I have hereunto subscribed my name this 10th day of November, 1920.

WILLIAM H. W. HAMILTON.
